EDWIN W. TUCKER AND CHARLES L. GRUNDELL, OF SAN FRANCISCO,
CALIFORNIA.

OIL-BURNING SYSTEM.

SPECIFICATION forming part of Letters Patent No. 758,224, dated April 26, 1904.

Application filed June 26, 1902. Renewed September 19, 1903. Serial No. 173,782. (No model.)

To all whom it may concern:

Be it known that we, EDWIN W. TUCKER and CHARLES L. GRUNDELL, citizens of the United States, residing at and whose post-office addresses are, respectively, 818 Page street and 1638 Hyde street, in the city and in the county of San Francisco and State of California, have invented certain new and useful Improvements in Oil-Burning Systems; and we do hereby declare the following to be a full, clear, and exact description of said invention, such as will enable others skilled in the art to which it most nearly appertains to make, use, and practice the same.

This invention relates to improvements in apparatus for burning fuel-oils, and relates particularly to the adaptation of such apparatus to steam-generating plants.

The invention consists, primarily, of the combination, with a steam-generating boiler, of an air-compressor and receiving-tank with means for maintaining a normal pressure therein, an oil and air heater with its contents under the pressure of the air-compressor and fed by an oil-pump, automatically maintaining a normal level in the said heater, strainers interposed in the pipe-line from the main storage-tank to the heater, means for heating the oil in the heater, suitable piping from the heater to the furnaces of the boiler, special furnace-fronts consisting of a box-like structure normally flush with the face of the boiler-front and having interior chambers extending into and subjected to the heat of the furnace, cone-shaped openings through said fronts flaring inwardly to form flame-inlets for the burners and internally insulated from the extreme heat thereof, the whole special furnace-front being either hinged or bolted to the front of the boiler, so as to be readily swung free therefrom to facilitate access to the burners and to the furnaces, the air and oil supply to the burners fixed to the furnace-front being swivel-jointed on the same axis and adapted to swing with the said front, the said air-supply being led through and superheated in the internal chambers of the said furnace-front before entering the burners, suitable valves, gages, and secondary

mechanisms in connection with above main groups to comprise a complete, co-operative, and equivoiced system for burning fuel-oils, as will be specifically described in the following specification, taken in connection with the accompanying drawings, in which—

Figure 1 is a diagrammatic side elevation of the various apparatus and mechanisms forming the subject of this invention. Fig. 2 is a vertical cross-section through the furnace and boiler, taken on the line $z z$, Fig. 1. Fig. 3 is a front elevation of the special furnace-front, showing form and mode of connecting air and fuel pipes to burners. Fig. 4 is a vertical cross-section of the special furnace-front on the line $z' z'$, Fig. 2, looking outward, showing the outlines of the internal chambers therein. Fig. 5 is a detail view of the alarm mechanism. Fig. 6 is a detail view of the hinge-valve B^6 .

In the drawings similar letters of reference refer to similar parts throughout the several views.

The invention will be described with particular reference to its application to marine conditions, wherein economy of water necessitates the use of air instead of steam as a vehicle for atomizing the oil. The extra drain on the boilers in the use of steam as a vehicle, as well as many advantages incident to the use of compressed air, commends the latter in a variety of instances.

The steam generated in the boiler A passes into the pipe A' for distribution. Steam is led into the actuating-cylinder B of the air-compressor through the pipe B', which operates to compress the air in the cylinder B², from which it passes to the receiving-tank B³. The pressure of air is regulated by the automatic pressure-governor B⁴ on the pipe B', set to the desired pressure and balanced by the opposing pressures of the steam and air through the pipe B⁵ and the compensating-spring of the governor. The pop-valve B⁶ acts as a safety against excess of pressure. From the tank B³ the air passes through the pipe B¹² to the distributing-pipe B⁸ and also through the check-valve B⁷ to the oil-heater C.

The oil-heater C is supplied from the main

oil-storage reservoir or settling-tank by the duplex pump D through the pipe D³ and spring check-valve D¹⁴. The pump is actuated by steam from the pipe A². The oil is pumped 5 through the strainers D', arranged between the valves D² on the oil-conduit D³. The strainers are arranged in two separate sets between valves, so that the oil may be diverted while 10 one set is inoperative without interrupting its flow to the heater. The steam-pipe A² enters the heater C and is coiled within the body thereof to heat the air and oil therein, passing thence to the condenser or hot well of the steam-plant to save the condensation resulting from radiation. 15 The automatic action of the pump D is controlled by the throttle D⁴, operated by the float D⁵ within the heater C. The lever D⁶ and its trunnion-pivot are hollow and open to the float D⁵. This permits seepage into the 20 float to be drawn off through the pet-cock D¹⁵, screwed onto the end of the trunnion. For facility of access the lever D⁶ of the float is pivoted in the manhole-plate D', covering the opening in the tank. By this arrangement the 25 whole valve mechanism is readily accessible. The plate D' has the graduated quadrant D⁸ affixed thereto to act in conjunction with the exposed end of the lever D⁶ as an index to show the oil-level in the tank C. The ball- 30 float D⁵ is adapted to float upon the surface of the oil. To avoid collapsing of the ball by the air-pressure, a small hole is drilled in the top of the ball to admit the air. When the ball drops below the mean level, it opens the throttle D⁴, admitting steam to the actuating-cylinder of the pump D, which raises the level of the oil. Should the oil-level fall and the pump fail to operate, steam (through a by-pass 35 in the throttle) would be admitted to the alarm-whistle D¹⁰, which would call attention to the failure of the pump. This effect would also be produced by an abnormal rise of the oil-level. The compressed air entering the heater C exerts a pressure on the oil therein, causing 40 it to flow through the distributing-pipe D¹¹ to the burners E. Any gases arising from the heated oil may be evacuated through the valve D¹², thence forward through the distributing-pipe B⁸ to the burners E, absolutely removing 45 all chances of explosion.

The type of burner shown forms the subject of a separate application for patent, and consists of a fitting having an internal dividing-wall, an air-pipe forming the shell of the 50 burner screwed into the fitting and terminating in a tip, an oil-tube centrally located in said shell and screwed into the dividing-wall of said fitting from behind in such a manner as to be readily withdrawn and replaced, a 55 mixing-head screwed onto the end of the oil-tube near the burner-tip and adapted to entirely fill the bore of the burner-shell and having an extension into the bore of the tip, spiral 60 grooves cut into the periphery of the mixing-head to give the escaping air a cyclonic whirl

as it picks up the globules of oil squirting from the holes in the mixing-head and spattering against the adjacent walls of the tip, means for controlling and regulating valves located on the respective supply-pipes adjacent the burner, and stop-valves adjacent the regulating-valves operated simultaneously by a throttle-lever.

From the distributing-pipe D¹¹ the oil passes through the valves E' E' to the oil-conduits 75 of the burners. The swivel-joint E³, located on the axis of the hinge F' of the furnace-front F, permits the latter to swing upon its axis without oil-leakage. The joint also acts as a valve to shut off the oil-flow when the furnace-front is swung outward. From the distributing-pipe B⁸ the air is led through the swivel-joint B⁹ (similar in every respect of operation to E³) to the inlet F² of the internal circulation-chambers F³ of the furnace-front 80 F, around and through which it passes, absorbing the radiated heat from the furnace before passing through the outlets F⁴ to the burners. From the outlets F⁴ the air passes through the valve E⁴ E⁵ to the air-conduit of 85 the burners, combining with the oil and escaping in combustion in the furnaces. The valves E⁶ and E⁷ act as regulating-valves to control the proportions of oil and steam admitted to the burner. The valves E⁸ and E⁹, 90 operated by the throttle E¹⁰, control the volume of combustion independent of the proportions thereof.

The special furnace-fronts F combine four radical improvements in this art—to wit, superheating the air or steam used in combustion, keeping the furnace-fronts cool by using the radiated heat formerly lost in fire-brick fronts, and rendering the burners and furnace-space easily accessible and, further, rendering 100 the change from oil-fuel to solid fuel quickly and easily made by unhinging the front and substituting one specially adapted to the form of fuel.

Under ordinary conditions the furnace-front 105 may be cast in one integral piece, the internal chambers being suitably cored. It may be of any desired shape or contour, as conditions may demand, and is hung upon the hinges F', set out from the face thereof, to allow a free swing and room for the swivel 110 in the pipe connections. It is held snugly to the face of the boiler-front X by the bolts F⁵, compressing the non-combustible gasket F⁶ between. The flared burner-openings F⁷, subjected to the extreme heat of the burners, are 115 therefore lined with the graphite lining F⁸, held in place by the removable ring F⁹. The bushing F¹⁰, through which the burner extends, is slightly larger than the burner to 120 give a draft of air around same. The opening F¹¹, covered by the swing-plate F¹², gives a peep-hole view of the interior of the furnace. Should the air-supply for any reason 125 fail, steam may be instantly substituted by 130

opening the valve A³ on the pipe A⁴, permitting steam to enter and follow all the paths the air would follow excepting through the heater. To draw off any water which may collect within the special furnace-fronts from condensation, the petcocks F¹³ are provided.

The temperature of the air entering the burners can be graduated to any degree by opening the valve B¹¹, leading from the distributing-pipe, mixing the air direct from the compressor with the superheated air issuing from the furnace-fronts. Should it be desired to cut out the superheating-chambers in the furnace-front, close the valves B¹⁰ E⁴ and open B¹¹. This gives a direct flow from distributing-pipe to burners. To blow out the oil-distributing pipe D¹¹ and burners E with steam or air, close valve D¹³ and open B¹⁴. This is advisable when shutting down the plant to prevent any oil from remaining in pipes or from running into the furnaces when the boiler is not under steam. Air is admitted through the damper-door X' in the usual manner, except that the bridge-wall G, which has an upwardly-curved face, gives it an upward trend into the path of the flame to prevent any cold air from passing into the furnace, which would otherwise form a strata of cold air between the combustion and the bottom of the furnace. The burners are arranged in sets, so that under a "slow bell" alternate burners may be shut down and the remainder regulated. In this manner the heat is more evenly distributed than it could be where all the burden was placed upon a single burner. This arrangement of the burners in sets amounts to more than a double use, inasmuch as a new result is accomplished. By this arrangement it is possible to cut down combustion to one-half and keep all ignited burners operating at full capacity, insuring perfect combustion and an equal distribution of heat under the boilers. This is a very important item in stormy or foggy weather, when it may be necessary to run for days under half-speed. No burner can be expected to accomplish as perfect combustion under half capacity as under full blast. Further, only the forward portion of the boiler is operated upon by the flame, resulting in an irregular generation of steam.

It is obvious that this system may be adapted to other circumstances than those specifically above described and that changes may be made in the location of certain valves, &c., without departing from the spirit of this invention.

Therefore what we claim, and desire to secure by Letters Patent, is—

1. In an oil-burning system the combination with a steam-generator of an air-compressor, a receiving-tank therefor, and means for automatically maintaining a given pressure in said tank; a heater heated by steam from said gener-

ator, and adapted to contain fuel-oil under the pressure of air from the air-compressor, means for pumping oil from the source of supply through strainers arranged in parallel, whereby the flow may be diverted without stoppage, and means whereby a given oil-level is automatically maintained in the heater; distributing-pipes leading from the heater below the oil-level and from the air-compressor to the burners under the steam-generator; and distributing-pipes leading from the heater above the oil-level to special furnace-fronts, containing internal superheating-chambers exposed to the radiated heat from the furnaces, from which the air is led to the burners: substantially as described. 80

2. In an oil-burning system the combination with a steam-generator, of an air-compressor, a receiving-tank therefor, and means for maintaining a given pressure in said tank; a heater heated by steam from the said steam-generator, and adapted to contain fuel-oil under the pressure of the air from the air-compressor; a pump adapted to overbalance a loaded check-valve to supply the said heater from the source of the oil-supply; means for maintaining a given oil-level in the said heater, consisting of a float pivoted in the manhole-plate resting upon the oil, and suitably connected with the throttle controlling the action of said pump and an alarm mechanism, whereby the failure of said pump to perform its function will divert the steam to the alarm; distributing-pipes leading from the heater below the oil-level to the burners under the steam-generator; and distributing-pipes leading from the said heater above the oil-level to the said burners; means for letting steam into the air-supply pipe; and means for letting steam or air into the oil-distributing pipes between the heater and the burners; substantially as 105 described.

3. In an oil-burning system the combination of a steam-generator; an air-compressor; and an air and oil heater; with a furnace-front consisting of a front hinged to the boiler-front, and having internal chambers subjected to the radiated heat of the furnace, openings therethrough, having oil-burners fixed therein; oil and air supply pipes swiveled on the axis of the hinge of said furnace-front, the oil passing direct to the burner and the air passing into and through the internal chambers of said furnace-front before entering the burner; substantially as described. 115

4. In an oil-burning system, the combination with a steam-generator, an oil-supply apparatus, an air-supply apparatus, of a furnace-front having internal chambers exposed to the action of the heat, said front being hinged, an air-pipe from the air-supply apparatus to said chambers and to the burners direct, an oil-pipe from the oil-supply apparatus which connects with the burners, said chambers connecting 125

with the burners to supply air, and hinge-valves on said air and oil pipes whereby the supply of air and oil can be cut off.

5. In an oil-burning system, the combination with a furnace-front, burner-openings thereon, air-spaces in the furnace-front around said burner-openings, said spaces connected with the burners, of means whereby air under pressure is supplied to said burners through said spaces, means for supplying oil to said burners, means whereby said air is supplied directly to the burners, omitting the air-spaces and means whereby steam is supplied to the air-pipe.
- 15 6. In combination with an oil-burning system, a furnace-front hinged to the boiler-front and having a plurality of burners projecting therethrough, internal chambers in the furnace-front being exposed to the heat of the

furnace and through which air passes to the burners, of means for supplying oil to the burners, means for supplying air to the chambers, and valved hinges on said supply means whereby the supply of oil and air can be cut off.

7. In combination with an oil-burning system, a heater, adapted to contain fuel-oil and having a manhole-plate near the oil-level; a float trunnioned in said manhole-plate, and having a hollow stem and trunnioned whereby the seepage into the float may be drawn off: substantially as described.

In testimony whereof we have hereunto set our hands this 16th day of June, 1902.
